DESIGN FOR A WRINGER

Marshall R. Scott, Ripon, Wis., assignor to Barlow & Seelig Mfg. Co., Ripon, Wis., a corporation of Wisconsin

Application April 25, 1935, Serial No. 56,557

Term of patent 14 years

To all whom it may concern:

Be it known that I, Marshall R. Scott, a citizen of the United States, residing at Ripon, in the county of Fon du Lac and State of Wisconsin, have invented a new, original, and ornamental Design for a Wringer, of which the following is a specification, reference being had to the accompanying drawing, forming part thereof.

The figure is a perspective view of a wringer showing my new design.

The appearance of the rear of the wringer is substantially the same as the front.

I claim:

The ornamental design for a wringer substantially as shown and described.

MARSHALL R. SCOTT.
